DESIGN FOR A PIANOFORTE

Willie Evans, Finsbury Park, London, England

Application February 15, 1936, Serial No. 61,187
In Great Britain January 8, 1936

Term of patent 14 years

To all whom it may concern:

Be it known that I, Willie Evans, a subject of the King of England, residing at London, England, have invented a new, original, and ornamental Design for a Pianoforte, of which the following is a specification, reference being had to the accompanying drawing, forming part thereof.

I claim:

The ornamental design for a pianoforte, as shown,

WILLIE EVANS.
